Primary Examiner — Darlington Ly*Assistant Examiner* — Katherine A Holbrow(74) *Attorney, Agent, or Firm* — Shumaker & Sieffert, P.A.(57) **CLAIM**

The ornamental design for a display screen with graphical user interface, as shown and described.

DESCRIPTION

FIG. 1 is a front view of a display screen with graphical user interface, showing a first embodiment of the new design; FIG. 2 is a second embodiment thereof;

FIG. 3 is a third embodiment thereof;

FIG. 4 is a fourth embodiment thereof;

FIG. 5 is a fifth embodiment thereof;

FIG. 6 is a sixth embodiment thereof; and,

FIG. 7 is a seventh embodiment thereof.

The broken lines illustrate the display screen and portions of the graphical user interface, and form no part of the claimed design.
